UNITED STATES PATENT OFFICE.

HOMER CHARLES, OF RAPID CITY, SOUTH DAKOTA.

EXPLOSIVE-ENGINE.

No. 906,105.

Specification of Letters Patent.

Patented Dec. 8, 1908.

Application filed May 17, 1904. Serial No. 208,437.

To all whom it may concern:

Be it known that I, HOMER CHARLES, of Rapid City, in the county of Pennington and State of South Dakota, have invented 5 certain new and useful Improvements in Explosive-Engines; and I hereby declare that the following is a full, clear, and exact description thereof, reference being had to the accompanying drawings, which form part 10 of this specification.

This invention is an improved explosive-engine, adapted to be operated by hydro-carbon mixtures, and especially designed for burning the heavier hydro-carbon oils, 15 such as ordinary petroleum, and the object of the invention is to dispense with valves and moving or adjusting parts as far as possible, also to dispense with electrical and other complex igniting devices;—and to produce a simple, efficient, self-contained explosive engine, with the fewest possible number of parts, and which will be capable of high speeds, develop great power, be economical in construction and in consumption of fuel, 25 and perfectly reliable under all conditions of service.

The invention consists in the novel construction and combinations of parts herein-after set forth in the claims following the 30 appended description of the engine illustrated in the accompanying drawings which I will now describe in detail to impart a clear understanding of the invention.

In said drawings, Figure 1 is a longitudinal vertical sectional elevation of the complete engine. Fig. 2 is a horizontal longitudinal section therethrough in the plane of the main-shaft. Fig. 3 is a detail vertical horizontal section showing the arrangement 40 of ports. Fig. 4 is a side elevation of the engine. Figs. 5, 6, and 7 are details of the engine showing specific construction of parts that will be more fully described.

The engine proper is preferably mounted 45 on a hollow base or reservoir A, adapted to contain fluid hydro-carbon to carburet the air and form the explosive mixture. The engine cylinder B is preferably water-jacketed and may be formed in one casting with 50 one half C of the crank-housing or pumping chamber, the other half C' of said housing being bolted to the first half and to the base. The main shaft D is journaled in suitable

bearing in said housing and is provided with a suitable crank, preferably formed by disks 55 d and wrist-pin d', said wrist-pin being connected by a piston-rod e directly to the piston E which operates in the cylinder B, and serves both as the engine piston proper, and as the valve controlling the various ports of 60 the engine: the said piston E also serves as the pumping piston, to alternately draw explosive mixtures into the crank or pumping chamber F (within housing C, C') and to expel such mixtures from the latter chamber 65 into the exploding chamber b, as hereinafter described.

The outer end of the cylinder B is closed by a peculiar igniting head G, which has a chamber g in its inner end communicating with the chamber b by a reduced centrally located opening g', and in its outer end is a chamber g² to which access can be had through a central opening g³; and chamber g² may have radial outlets g⁴ if desired. 75 The wall between chambers g, g², is preferably heavy, and the chamber g is preferably isolated from the outer walls of the head by an annular recess G² leaving an annular ring of metal G' between chambers b and g, 80 which when once heated will remain hot for a long time, and is protected from direct loss of heat by radiation by the chambers b, g, and the recess G². This head I term an ignition head, and before starting the engine it can be heated by a gasolene or other blower, introduced through opening g³, to a temperature sufficient to ignite the explosive mixture when compressed thereagainst, and when once heated, the exploding gases maintain it at a sufficiently high temperature to insure the ignition of the explosive mixtures. In actual practice such heads have retained their heat sufficiently to allow resumption of work by the engine after fifteen and twenty 90 minute intervals without re-application of external heat.

Explosive mixtures are admitted into the exploding chamber from the pumping chamber F, through ports H, preferably arranged as in Fig. 3 and controlled by the main piston E; while the burned gases are exhausted through a port I which opens into the exploding chamber between and substantially in line with the terminals of 105 the ports H, so that the exhaust port is

- opened about simultaneously with the inlet ports. It will be observed that the inlet ports H communicate with the exploding chamber at nearly diametrically opposite 5 points, and slightly below the axial plane of the cylinder, and on opposite sides of the exhaust port. The said inlet ports moreover, are so arranged that they direct the in-rushing gases toward the front and upper 10 part of the exploding chamber, in such manner that the incoming explosive gases tend to drive the burned gases out of the cylinder, and when the ports are properly arranged and proportioned nearly all of the burned 15 gases will be expelled from the exploding chamber before any of the fresh gases can escape, and in practice the loss of fresh gases is practically *nil*,—as compared with other engines heretofore used.
- 20 By having the inner ends of ports H below the axial line of the piston, the close fit required between the piston and cylinder, in order to properly close the ports is maintained unaffected by the wear therebetween.
- 25 As above stated, the base A is preferably a hydro-carbon tank or reservoir, and within this reservoir I suspend a carbureter J which comprises a hollow casting bolted to the base of the engine or top of the tank, 30 and depending thereinto below the surface of the oil. This carbureter has an air inlet passage j, separated from the mixing chamber j' by a wall j², but communicating with the latter through a passage j³ at the bottom of wall j². The mixing chamber J of the carbureter connects with a port J' leading through the base of the cylinder and adapted to communicate with the pumping chamber F when the piston is in its outer 35 most position, so that at this time the explosive mixtures are drawn into the chamber F. The piston E controls the opening and closing of port J', and in practice this port is only momentarily opened, so that before it is open a partial vacuum is created 40 in the chamber F, which causes a fierce and violent inrush of air through the carbureter into the crank-chamber when the port J' is opened as hereinafter described.
- 45 The oil or fluid hydro-carbon is admitted in properly regulated quantities into the bottom of passage j through a small aperture j⁴ controlled by a regulating valve k on the lower end of a stem K which extends to a point above the base and is normally 50 pressed down, so as to close the port j⁴, by means of a spring K' interposed between an arm L and a collar K² on the stem K.
- The arm L is attached to an adjustable 55 bracket L' slidably mounted on a fixed guide rod M, provided with adjusting and jam nuts m, m' on its upper end, by which the bracket can be vertically adjusted to regulate the pressure exerted by spring K'. The

valve k may be formed by properly pointing 65 or shaping the lower end of stem K, or any suitable form or construction of such valve may be used; it is preferably one which will give a larger inlet area the further the valve is unseated, so that the valve will be quite 70 sensitive in action. In practice this valve not only regulates the normal supply of oil—but also serves as the throttle valve,—and it serves as the governing valve, for which purpose it is operated as follows:— 75 On the main shaft is a sliding collar N having a conical end N' which is adapted to engage a beveled lug o on the upper end of a sliding bar O, suitably guided below the main shaft and above the base A. The 80 lower end of bar O is pivotally connected with one end of a lever P, fulcrumed at p on a stud rising from the base A, and the other free end of said lever P extends beside the stem K and has a notch p' in its 85 upper surface which may be engaged by the handle K³ on stem K, and when this handle is rested in said notch, the valve k, will be opened and oil will flow into the passage j. The valve k should not be thus opened until 90 the firing-head has been heated and the engine is to be put in operation. The collar N is shifted on the shaft by means of a governor, which preferably comprises bell-crank levers Q pivoted on the fly-wheel, and 95 having their inner ends engaging the groove of the collar N, while their outer ends, project through the web of the wheel to the outer face thereof, and are provided with weights R which when the velocity of the 100 main shaft reaches the predetermined limit, will move out by centrifugal action and cause the levers to shift the collar and cause it to operate the lever P and more or less close the valve k. Opposite arms G may be 105 connected by springs S which oppose the tendency of the weights to separate by centrifugal action; and means are provided for adjusting the tension of such springs, so that the speed at which the governor will 110 cut off the oil supply can be regulated with great nicety.

As the crank-chamber is used as a pumping and compressing chamber, the bearings of the shaft should be stuffed as air and gas tight as possible, to prevent escape of the explosive mixture on the in-stroke of the piston, or admission of air on the out-stroke of the piston. Air is admitted freely to the tank A through suitable apertures 115 which may be screened to prevent dust or dirt entering therein. The oil may be kept below the upper inlet end of air passage j by any suitable means.

Operation: The parts being in operative 125 condition, valve k closed by turning stem K so that its handle is free from lever P; the tank is then filled with a suitable hydro-

carbon, such as petroleum, and then the igniter head is heated by the application of a blow-torch or in other suitable manner. The valve *k* is then opened by engaging handle *K* with lever *P*, and the fly-wheel is turned until the piston is moved out (on the suction stroke), creating a partial vacuum in chamber *F*, until the piston uncovers port *J*, whereupon a violent inrush of air takes place through passage *j*, carburetor *J* and port *J'* into chamber *F*, the air sweeping up the oil in the bottom of passage *j* atomizing it and commingling therewith as it rushes into the chamber *F*. The wheel is further turned until the piston moves inward (on the explosion stroke) compressing the explosive mixture in chamber *F*, until ports *H* and *I* are uncovered, whereupon the explosive mixture rushes into the exploding chamber and fills the latter; another half turn of the main shaft forces the piston back, closes ports *H*, *I*, and compresses the explosive mixture until it is ignited by the heat of the firing cap, whereupon the piston is driven back by the exploding gases and the engine runs automatically so long as the supply of fuel is maintained; or until the valve *k* is closed.

In the cycle of operations, the piston on its explosive stroke compresses a supply of carbureted gases or air in the chamber *F*, and as soon as the ports *I*, *H*, are uncovered this compressed explosive gas rushes into the cylinder and by reason of the peculiar arrangement of the ports drives out the burned gases and takes their place; on the return momentum stroke of the piston, the explosive gases in the cylinder are compressed to a high degree, and simultaneously a partial vacuum is created in the pumping chamber *F*, which is maintained until just before the piston reaches the limit of its outward stroke, when port *J'* is uncovered and a fresh supply of air mixed with vaporized or atomized oil is sucked into the chamber *F*. The compression of the gases in chamber *b* and the heat of the ignition head, suffices to raise their temperature to the ignition point, and they are automatically ignited at the proper moment.

I have practically tested this engine for months; it runs smoothly and comparatively noiselessly at high speeds. An eight horse power engine of this construction has been operated ten hours with two gallons of kerosene.

It will be observed that my engine needs practically but three moving parts, to wit: main-shaft, piston, and piston-rod, no other moving parts are essential to the operativeness of the engine, and it is obvious that the cost of maintenance and repairs will be reduced to the minimum and the effectiveness of the engine increased to the maximum, by such simplicity of construction.

Having thus described my invention what I therefore claim as new and desire to secure by Letters Patent thereon is:

1. In an explosive engine, a working chamber, a compression chamber, a single piston between said chambers and working in both of them, inlet ports leading from the compression chamber to the working chamber, an exhaust port leading from the working chamber and placed between the said inlet ports, and an inlet port connecting said compression chamber with a suitable source of fuel supply, all said ports being controlled by the aforesaid piston. 70

2. In an explosive engine, a working chamber, a compression chamber, a single piston between said chambers and working in both of them; inlet ports leading from the compression chamber to the working chamber, said inlet ports communicating with the working chamber at diametrically opposite points, an exhaust port in said working chamber, said exhaust port lying at a point to the rear and approximately midway between the inlet ports, and an inlet port connecting the compression chamber with a suitable source of fuel supply, all said ports being controlled by the aforesaid single piston. 75

3. In an explosive engine, a working chamber, a compression chamber, a piston between said chambers and working in both of them, inlet ports communicating with the working chamber at diametrically opposite points, said inlet ports terminating in a single connecting opening in the compression chamber whereby the explosive charge taken in through one opening in the compression chamber is delivered at two opposed points within the working chamber, an exhaust port in said working chamber, said port lying between the inlet ports and to the rear of them, and a fuel supply passage connecting the compression chamber with a suitable source of fuel supply, said supply passage terminating in a suitable delivery port in the compression chamber and a carbureting device within the said supply passage, all the aforesaid ports being controlled by the single piston aforementioned. 90

4. In an explosive engine, a working chamber, a compression chamber, a single piston between said chambers and working in both of them; inlet ports leading from the compression chamber to the working chamber at diametrically opposite points, an exhaust port in said working chamber, said exhaust port lying at a point to the rear and approximately midway between the inlet ports, said inlet ports being so constructed as to conduct the fresh fuel above and to the rear of the burned gases and to thereby force them out through the exhaust port, and an inlet port connecting the compression chamber with a suitable source of 110

fuel supply, all said ports being controlled by the aforesaid single piston.

5. In an explosive engine, a working chamber and a compression chamber, a single piston between said chambers and working in both of them, passages leading from said compression chamber to said working chamber and terminating in diametrically disposed inlet ports in the working chamber 10 and in a single port in the compression chamber, an exhaust port in said working chamber, said exhaust port lying to the rear and between the inlet ports, the single piston being adapted to control all the aforesaid 15 ports and to close them only momentarily, whereby a partial vacuum is created in the compression chamber before its inlet is opened.

6. In an explosive engine, a working chamber and a compression chamber, a single piston between said chambers and working in both of them, passages leading from said compression chamber to said working chamber and terminating in diametrically disposed inlet ports in the working chamber 20 and in a single port in the compression chamber, an exhaust port in said working chamber, said exhaust port lying to the rear and between the inlet ports, said inlet ports being adapted to conduct the fresh explosive charge above to the rear and behind the burned gases, thereby forcing the same out through the exhaust port, the single piston being adapted to control all the aforesaid 25 ports and to close them only momentarily, whereby a partial vacuum is created in the compression chamber before its inlet is opened.

7. In an explosive engine, a working chamber and a compression chamber, a single piston between said chambers and working in both of them, passages leading from said compression chamber to said working chamber and terminating in diametrically disposed inlet ports in the working chamber, 30 an exhaust port in said working chamber, said exhaust port lying to the rear and between the inlet ports, a fuel supply passage connecting said compression chamber with a suitable source of fuel, said passage terminating in a delivery port in said compression chamber, the single piston being adapted to control all the aforesaid ports and to close them only momentarily whereby a partial 35 vacuum is created in the compression chamber before its inlet is opened.

8. In an explosive engine, a working chamber and a compression chamber, said working chamber being formed integrally with one half of the compression chamber and the other half of the compression chamber being detachably fastened thereto, suitable inlet 40 passages connecting the working and compression chambers, said passages terminat-

ing in diametrically disposed delivery ports 65 in the working chamber and in a single port in the compression chamber, an exhaust port in the working chamber, a supply passage connecting the compression chamber with a suitable supply of fuel, said supply 70 passage terminating in a delivery port opening into the compression chamber, all said ports being controlled by a single piston which is mounted between the aforesaid compression and working chambers and is adapt- 75 ed to work in both of them.

9. In an explosive engine, a working chamber and a compression chamber, said working chamber being formed integrally with one half of the compression chamber and 80 the other half of the compression chamber being detachably fastened thereto, suitable inlet passages connecting the working and compression chambers, said passages terminating in diametrically disposed delivery 85 ports in the working chamber and in a single port in the compression chamber, an exhaust port in the working chamber, a supply passage connecting the compression chamber with a suitable supply of fuel, a 90 carbureting device in said fuel supply passage, said supply passage terminating in a delivery port opening into the compression chamber, all said ports being controlled by a single piston which is mounted between the 95 aforesaid compression and working chambers and is adapted to work in both of them.

10. An engine having an outlet port from the exploding chamber, and inlet ports leading into said exploding chamber on opposite 100 sides of the outlet port, the delivery openings of said inlet ports being beveled in the direction of the length of the exploding chamber, whereby they are adapted to direct the incoming fresh gases toward the other 105 end of the exploding chamber and above and behind the burned gases so as to drive the latter out of the chamber; with a main piston operating in both the pumping and exploding chambers, and controlling all the ports 110 thereof, and adapted to produce a partial vacuum in the pumping chamber before it opens the inlet port thereof, substantially as described.

11. In an explosive engine, the combination of a pumping chamber, an exploding chamber, an inlet to the pump-chamber, an outlet from the exploding chamber, and ports leading from the pumping chamber to the exploding chamber and communicating 115 with the latter on opposite sides of the outlet port, through openings in the walls of said exploding chamber, said openings being beveled in the direction of the length of the said exploding chamber whereby said beveled openings are adapted to direct the entering gases into the exploding chamber in such manner that they will expel the burned 120 125

gases; with a single main piston operating in both the pumping and exploding chambers, and controlling all the ports thereof, and adapted to produce a partial vacuum in the pumping chamber before it opens the inlet port thereof, substantially as described.

In testimony that I claim the foregoing

as my own, I affix my signature in presence of two witnesses.

HOMER CHARLES.

In presence of—

L. E. WITHAM,
JAMES R. MANSFIELD.
